UNITED STATES PATENT OFFICE.

GEBHARD JAEGER, OF COLUMBUS, OHIO.

BATCH METER FOR CONCRETE MIXERS.

Application filed September 20, 1928. Serial No. 136,498.

This invention relates to concrete mixing machines more particularly of the kind in which a rotary, tiltable mixing drum and loader therefor are employed. One of the objects of the invention is to provide mechanism whereby an annunciator, audible and visual, is actuated upon the occurring of a sufficiency of the mixing operation, said mechanism being adapted to be adjusted, 10 within limits, to vary the lapse of time when the annunciator shall be actuated and therefore for the number of rotations of the drum to be allowed for the mixing of the batch, and in combination therewith means for inter- 15 rupting and latching the drum during its tilting and mixing movement toward discharging position to prevent the discharge of the mixing drum until after the signal has been actuated thereby insuring that the de- 20 sired number of rotations of the mixing drum shall have taken place. Other objects will appear from the disclosure herein.

The invention is embodied in the example herein shown and described the feature of 25 novelty being finally claimed.

In the accompanying drawings forming part hereof—

Figure 1 illustrates in front elevation the meter mechanism and its containing box 30 with the cover of the box removed.

Fig. 2 is a horizontal section on the line II—II Fig. 1 exposing in top plan view the meter mechanism.

Fig. 3 is a detail in side view of the cam member and a retracting spring for the shaft carrying the cam member and timing device and also of the latch arm and its spring to effect the release of the latch arm from latching position.

Fig. 4 is a detail section on the line IV—IV Fig. 5 of the cam member showing its interior construction.

Fig. 5 is a section on the line V of Fig. 1.

Fig. 6 is a view in side elevation on a 45 smaller scale of the meter mechanism as applied to a concrete mixing machine, parts of said machine being broken off, the electric circuit of the signal being shown diagrammatically.

Fig. 7 is a detail top plan view of the meter and latching mechanism as shown in Fig. 4 with some parts omitted and some parts in section.

In the views 11 designates the mixing drum of an ordinary form which has a single opening at 11^a for charging it with con-

crete materials and discharging them when mixed. This drum is mounted on a suitable yoke 12 to turn on its axis, the yoke having trunnions journaled as at 12^a in a frame 60 to permit oscillation or tilting of the drum while being turned on its axis from charging to discharging position and reversely. The charging means to supply the drum with the sand, gravel and cement consists of a bucket 65 16 pivoted in the frame 30 by means of a pendent link 30^a to the lower end of which the bucket is connected. The bucket 16 has suitable means (not shown) for hoisting it to drum-charging position and lowering it 70 to the ground for receiving fresh supplies of concrete materials.

The mixing drum 11 has suitable means, operable independently of the means for tilting it, for turning it on its axis including an 75 annular rack 11^b engaged by a power driven pinion, as usual. The mixing drum also has means for tilting and discharging it including a large internal gear 13 fixed to the trunnion 12^a of the yoke engaged by a pinion (not shown) on a hand wheel 14. In a general way the features thus described or their 80 functional equivalents are common to many mixers now being marketed and it is thought a brief description of them will suffice for 85 the purpose of aiding in explaining the construction and mode of operation of the present cooperating elements which will now be described.

18 designates a box that is secured on a 90 cross bar of the frame, said box having mounted therein a worm gear wheel 19 to which is secured an arm 21 with an inclined end 21^a. Said worm wheel is fixed on a shaft 19^a that turns in suitable bearings 95 in the wall and cover of the box 18, and secured between the latter and the worm gear is a coiled spring 44 tending to turn the wheel and the members secured to shaft 19^a anti-clockwise. Hung in the 100 box 18 is a latch 22 provided with a laterally projecting pin 23 electrically insulated from said latch by suitable material as at 23^a (see Fig. 2). Engaging the worm wheel 19 is a shaft 24 having at one 105 end a worm 24^a engaging and operating the wheel 19 and at the other end worm gear 24^b engaged by a worm shaft 26 having at its opposite end an ordinary pinion 26^a engaged by the annular rack 11^b of the mixing 110 drum. In the practical operation when the drum is rotated the worm gear wheel 19 is

turned periodically, the shaft 24 being separably engaged with it as hereinafter explained. A reduced end of the shaft 24 beyond the worm 24^a carries a block 28 in 5 which said reduced end turns, said block being bifurcate at its upper end (see Fig. 2) and having a cross pin 29 bridging the forks referred to. The block 28 is guided by a vertical rod 54 secured between the top and 10 bottom of the box.

The lower end of the latch 22 is provided with a hook 22^a having a blunt end, and said latch is drawn by a spring 31 to throw the hook under the cross pin 29 when the worm 15 24^a is engaged with the worm wheel 19 to hold the worm so engaged.

Sliding horizontally in the lower portion of the box 18 is a rod 32 pivoted at its right hand end to a crank arm 33 on one end of 20 a shaft 34 journalled in the frame and having at its other a trip arm 35 so that by oscillating said trip arm the rod 32 will be shifted longitudinally. On the bar of a bracket 36 fixed on the loader bucket is a 25 laterally projecting pin 36^a that, when the loader is raised to drum-charging position, strikes the trip arm 35 and shifts the rod 32 to the left (see Figs. 1 and 2). Within the box 18 the rod 32 is provided with a cam 30 member 37 that strikes a truncated corner of the block 28 when the latter is down to raise that member and the worm 24 the latter into engagement with the worm wheel.

The cam member 37 is of such form that 35 when the shaft 24 has been lowered to release the worm from the worm gear the block 28 rests on a pin 37^a on the guide bar 54 of the block 28 with the blunt end of hook 22 abutting against the cross pin 29. This construction assures the reengagement of the 40 hook 22 with the cross pin when the block has been raised by the cam member 37.

When pressure of the pin 36^a is removed from trip-arm 35 by the lowering of the 45 loader bucket a spring 38 tends to restore that arm and the rod 32 to position for reoperation upon the elevation of the loader bucket to charge the mixing drum.

In order to predetermine the number of 50 rotations to be made by the mixing drum prior to the operation of the annunciator the worm gear has secured to its side by a screw 41 a plate having an arm 21, said plate also having an arcuate slot 21^b through which the 55 said screw passes. Around the plate next the said slot is a scale marked with numbers designating the number of rotations of the mixing drum according to the position of the arm 21 when fixed with respect to the 60 worm gear 19. Superimposed on said slotted plate is a pointer member 46 held in fixed position with reference to the worm-gear by the same screw 41 passed through a round hole in said member 46 so that upon 65 loosening said screw the plate bearing the

arm 21 can be turned with respect to the pointer member and refixed with the pointer pointing as desired. It may be noted that the radial relation of the pointer to the worm gear is not changed but that the plate having the arm 21 is shifted with respect to the pointer and gear to time the rotation of the drum. 70

There is illustrated, in the example shown, an electrically operated horn 50, such as 75 used on automobiles, the wiring of which is connected to the pin 23, any source of electricity at 51, and ground at the box 18 as depicted in the diagram Fig. 6. Normally the circuit of the horn is open but when the inclined end 21^a of the arm 21 strikes the pin 23 the circuit is closed and the horn sounded as usual in such devices. The clockwise or timing swing of the arm 21 releases the block 28 from the hook 22^a, said 80 block together with the shaft 24 dropping away so that the worm is disengaged from the worm wheel with the blunt end of the hook abutting against the pin 29. If desired a manually operated switch 52 can be 85 inserted as indicated in the circuit (see Fig. 6) to insure an open circuit when the machine is not in use. 90

Pivoted at 55 to the rear wall of the box 18 is a long latching arm 56 extending inclinedly through a suitable slot in the top of the box, said lever having at its upper end a laterally extending member with a curved portion 56^a, the end of which forms a latch. The slot in the top of the box has a surrounding lip 57 and the lever 56 carries pivoted to it at 58 a cover 59 that is adapted to keep concrete materials from falling into the box and thereby interfering with the operation or impairing the parts of the mechanism 100 therein contained. 105

Secured on the rim of the internal gear 13 is a lug 60 having a laterally projecting pin 61. The pin 61 is so located that when the latching arm is down the pin 61 is engaged 110 by the latching arm and the tilting progress of the mixing drum arrested shortly before it reaches discharging position.

On the shaft 19^a is secured a hollow or internal cam member 63 the larger portion of 115 the operating surface of which is concentric with the axis of the shaft 19^a said surface terminating at one end in a recess 63^a. The latch arm 56 is provided with a lateral pin 64 on which is a roller bearing fitting in a cavity of the internal cam member. The cam member is secured on the shaft 19^a in such position that the latch arm is normally held down by the internal cam member and against the force of a spring 56^b in position 120 to arrest the tilting progress of the drum toward discharging position and also so that the cavity of the recess 63^a will be turned to position to permit the roller bearing 125 to enter said recess and consequently 130

the removal of said arm from the drum latching position under the influence of the spring 56^b. To relieve the roller and cam of some of the friction at the start when the 5 roller is to come out of the recess 63^a and the latch arm is to be pulled down to latching position the rear wall of the box is provided with a stop 18^b to sustain the latch arm with the roller not as fully in contact with the 10 walls of said recess as it would be if the pull of the spring 56^b held the roller in such contact. The box cover 18^a has a suitable hole closable with a removable cover and through which hole a screw driver can be 15 inserted to turn the screw for adjusting and fixing the arm 21.

The operation which can be readily gathered from what has been said is briefly this: During the operation of the machine the rotation 20 of the mixing drum on its axis is constant in one direction as usual. The oscillation or tilting motion of the drum and the raising and lowering of the loader are, in the variety of the mixer referred to is, manually 25 controlled for the usual reasons. Normally the timing worm 24^a is disengaged from its gear, the engagement being effected by the charging operation of the loader. Assuming that the drum has just been supplied 30 with the concrete materials and the loader bucket lowered the arm 21 retracted the worm 24^a becomes engaged with the worm wheel 19 whereupon the rotation of the drum causes the turning of the arm 21 clockwise 35 slowly to position to strike with its end 21^a the pin 23 and release the block 28 which falls to the stop 37^a, the worm shaft at the same time being released by gravity from the worm gear. At the start of this 40 operation the latch arm 56 is thrown down in position to arrest the drum when the latter arrives nearly at its discharging position. The horn is sounded by the contact of the arm 21 with the pin 23 and instantly the 45 spring 44 retrieves the cam to latch-releasing position to permit the operation of the spring 56^b to draw the latch 56^a from the pin on wheel 13 and therefore permit the operator to turn the drum with the wheel 14 to discharging 50 position. The parts of the timing mechanism remain in this last described position and until the loader is raised to recharge the drum after which the operation is repeated.

The forms of the parts can be changed without departing from the gist of the invention as claimed.

In a copending application filed February 4, 1924, S. No. 690,355, to which reference is made, I have shown, described and claimed some of the features herein in perhaps modified form.

What I claim is:

1. In combination with a rotary and tilting mixing drum, a charging means and a

discharging means therefor, means for latching the discharging means including an arm with a pin thereon, a signal means, a metering means for the rotations of the drum including a worm gear and a worm separable with respect thereto actuated by the mixing drum, means carried with the worm gear for causing the actuation of the signal means upon a predetermined number of revolutions of the mixing drum, means carried with the worm gear consisting of a hollow cam having a recess in its rim said cam adapted to engage said pin to hold the latching arm in drum latching position pending the operation of the signal means. 75

2. In combination with a rotating and tilting element and means for causing such operation independently of each other, signaling means, means actuated by the rotations of said element to meter the rotations thereof, means for varying and limiting at will the number of rotations of said metering means, a latch for limiting the operation of the tilting means, and means for moving said latch into and out of latching position. 80

3. In combination with rotating and tilting elements and means for causing such operations independently of each other, signaling means, means actuated by the rotation of said element to meter the rotations thereof, means for limiting at will the number of rotations of said rotating and tilting device, a latch for limiting the operation of the tilting means, means for moving said latch into and out of latching position, and means for causing the operation of the signal by the metering device substantially contemporaneously with the release of said latch from latching position. 95

4. In combination with a rotated and tilting means, means for causing such operations independently of each other, timing means and signal means for the rotating means, a case containing said timing means, a movable latching means for the tilting means extending through an opening in the wall of the case, and a cover carried by said latching means to protect said opening. 105

5. In combination with a rotary and tilting mixing drum, a charging means for the drum, means for latching the drum from tilting to discharging position including an arm with a pin thereon, metering means for the rotations of the drum actuated by the drum and including a worm gear and a worm separable from the worm, means carried with the worm gear consisting of a cam having a recess, said cam adapted to engage the aforesaid pin of the latching arm to hold said arm in drum latching position during the metering operation, and means for drawing said latching arm from said drum latching position upon the completion of the metering operation. 115

6. In combination with a rotary and tilt-

120

125

130

- able mixing drum, means for causing such operation of the drum independently of each other, means actuated by the rotations of the drum to meter the rotations thereof, a 5 latch for preventing the tilting of the drum to discharging position during the metering operation, and means for moving said latch into and out of said drum latching position.
- 10 7. In combination with a rotary and tilt-able mixing drum, means for causing such operation of the drum independently of each other, a drum charging device, means actuated by the rotations of the drum to 15 meter the rotations thereof, a latch for preventing the tilting of the drum to discharging position during the metering operation, means for releasing said metering means, and means actuated with the metering means 20 to release said latch.
8. In combination with a rotary and tilt-able mixing drum, means for causing said operation of the drum independently of each other, a drum charging device, means 25 actuated by the rotations of the drum to meter the rotations thereof, a latch for preventing the tilting of the drum to discharging position during the metering operation, means for releasing said metering means, 30 means actuated with the metering means to release said latch, and means actuated by the drum charging means for resetting said metering means.
9. In combination with a rotatable mixing 35 drum that is tiltable while rotating to discharge it, means for normally latching the drum from being tilted to discharge it, a metering means for the rotations of the drum, and means for releasing the drum 40 latching means to permit the discharge of the drum upon the completion of the operation of the metering means.
10. In combination with a rotatable mix- 45 ing drum that is tiltable while rotating to discharge it, means for normally latching the drum from being tilted to discharge it, a metering means for the rotations of the drum operated by the rotation of the drum, and means for releasing the drum latching 50 55 means to permit the discharge of the drum upon the completion of the operation of the metering means.
11. In combination with a rotatable mix- 55 ing drum that is tiltable while rotating to discharge it, means for normally latching

the same from being tilted to discharging position, a metering means for the rotations of the drum, and means for automatically releasing the drum latching means to permit the tilting of the drum to discharge it 60 upon the completion of the operation of the metering means.

12. In combination with a rotatable and tilting mixing drum that is tiltable while rotating to discharge it, means for normally 65 latching the drum from being tilted to discharge it, a metering means for the rotation of the drum operated by the rotation of the drum, and means for automatically releasing the drum latching means to permit dis- 70 charging of the drum upon the completion of the operation of the metering means.

13. In combination with a rotating and tilting element and means for causing such operation independently of each other, 75 means actuated with the rotations of such element to meter the rotations thereof, a latch for limiting the tilting movement of said element, and means for moving said latch into and out of said tilting movement- 80 limiting position.

14. The combination of a frame, a tilting mixing drum carried by said frame, a latch for restraining said drum against tilting, and automatic mechanism for releasing said 85 latch after said drum has executed a predetermined number of revolutions.

15. The combination of a frame, a tilting mixing drum carried by said frame, a latch for restraining said drum against tilting, 90 and automatic mechanism driven from said drum for releasing said latch after said drum has executed a predetermined number of revolutions.

16. The combination of a frame, a tilting 95 mixing drum carried thereby, a latch for restraining said drum against tilting, a charging bucket for delivering a charge to said drum, automatic mechanism for releasing said latch after said drum has executed 100 a predetermined number of revolutions, and means for initiating the operation of said automatic mechanism when said bucket is moved to charging position.

17. The combination of a frame, a tilting 105 mixing drum carried thereby, locking means for restraining said drum from tilting, and automatic means for releasing said locking mechanism after a predetermined interval.

GEBHARD JAEGER.
